UNITED STATES PATENT OFFICE.

WILLIAM AUGUSTUS LEGGO, OF MONTREAL, QUEBEC, CANADA, ASSIGNOR
TO JACKSON RAE AND JAMES CRADOCK SIMPSON, BOTH OF SAME PLACE.

AUTOMATIC TELEGRAPHY.

SPECIFICATION forming part of Letters Patent No. 372,475, dated November 1, 1857.

Application filed June 25, 1886. Serial No. 206,962. (No model.)

To all whom it may concern:

Be it known that I, WILLIAM AUGUSTUS LEGGO, of the city of Montreal, in the district of Montreal and Province of Quebec, Canada, have invented certain new and useful Improvements in the Art of Automatic Telegraphy, and in the apparatus used therefor; and I do hereby declare that the following is a full, clear, and exact description of the same.

10 My invention has reference to the art of transmitting by telegraphy prepared messages, so as to be able to send in any given space of time a greatly-increased number of words, and comprises not only new means of transmitting 15 such messages, but also improvements in the apparatus which will insure the accuracy and clearness of messages sent at a high rate of speed.

The invention may be thus briefly described: 20 I may premise that in this case, as in all other automatic telegraphy, the messages are sent by the contact of the transmitting-styluses alternately with the conducting-surface of the revolving cylinder and the insulated spaces 25 marked upon it, and that these may be worked either positively or negatively, as desired. The insulated lines forming negative or positive of the message or messages to be sent are placed upon the surface of a cylinder, as has been already done; but in my instrument the 30 pen by which the signs or symbols are marked on the surface of such roller is during the operation of noting down such message always in contact with the cylinder, being moved 35 from side to side by ordinary or special means for the purpose, so as to describe a continuous message-line. The tablets carrying the pen by which the message is prepared and the styluses through which the message is con- 40veyed to the distant station are mounted above a screw-shaft, to which either may be attached at will, the motion of the cylinder being timed to suit the preparation and transmission of the message. To insure the rotation at the 45 same rate of speed of the cylinder and screw-shaft above mentioned, and thereby obviate the necessity of frequently adjusting the transmitting-stylus to the path of the pen, I mount upon the screw-shaft and the cylinder-shaft 50 similar gears, between which is an idle-wheel intermeshing with both.

The continuous message-line above mentioned is the positive or negative of the message to be transmitted, and is formed of an ink capable of breaking the current between the stylus and cylinder, such ink being preferably composed of commercial mucilage or gum-arabic diluted and colored. 55

For transmitting messages I may employ two batteries, one sending to line a plus (+) and the other a minus (-) current. In this case the transmitting-roller is connected to earth and one of these batteries interposed between each stylus and the line, it being evident that while one stylus is making electrical contact with the rotating roller, thus sending a current, either plus (+) or minus, (-), to line, the contact of the other is broken by the insulating-ink, and that when the positions, as regards the message of the styluses, are reversed, an 70 alternating current of different polarity will be sent to line. This arrangement of the two batteries may be employed when it is desired to repeat or retransmit messages at a distant station, the line being then preferably taken 75 through the magnet of a relay to earth and the action of such magnet upon its armature putting into circuit a local battery, which will operate, as before described, to work a pen for transcribing a message onto the cylinder. 80

I propose, also, to utilize secondary or induced currents for conveying a message, in which case only a single stylus, passing over either the negative or positive section of the prepared message, may be used. In this case 85 the local battery-circuit passes from the battery, through the primary wire of an induction or Ruhmkorff coil and transmitting-cylinder, back to battery, and the secondary circuit is the line-circuit taken to the earth at one end 90 and through the recording-instrument to earth at the other.

The secondary current can also be utilized to operate a polarized relay and work, by means of a local battery at a far station, the pen 95 for retransmission, as before described.

Instead of the ordinary key and circuit-breaker, I may in some instances make use of the key-board which I have invented, and which consists in a series of disks, upon which 100 are marked in metal the several signs to be noted on the cylinder, these disks being

mounted on keys, the depression of any of which will bring its disk in contact with a continuously-revolving roller, by which it is partially rotated and the circuit through the battery and the apparatus to be worked by the key completed.

For full comprehension, however, of my invention, reference must be had to the annexed drawings, forming part of this specification, in which—

Figure 1 is a side view of pen and operating mechanism; Fig. 2, a plan of same; Fig. 3, details of pen; Fig. 4, a side view showing apparatus for regulating motion of screw-shaft; Fig. 5, a view of line giving both negative and positive of message; Fig. 6, a diagram showing arrangement when two batteries are used; Fig. 7, a side view, and Fig. 8 a plan, of two styluses; Fig. 9, a diagram of apparatus for repeating message; Fig. 10, a diagram showing the working by secondary currents, and Fig. 11 a side view of one key of key-board.

Similar letters of reference indicate like parts.

A is the rotating cylinder, upon which the message is marked, of any desired construction, and mounted on shaft A', carried in suitable frame, in which is also set the screw-shaft B and slide B', carrying the tablets C and D, on the former of which are mounted the marking-pen and its operating mechanism and on the latter the stylus or styluses.

E is the pen-tube with nib E' split or slotted, as shown in Fig. 3, with two slits longitudinally of the pen-tube, and at the bottom another across these, transversely to the tube, so as to work with less ink. This tube E is attached by a flexible connection, E², to the siphon E³, communicating with the ink fountain or reservoir E⁴, arranged to be raised or lowered at will. The pen-tube E is secured to the pen-holder e, which is carried on a strong spring, e', from the tablet C, and has secured to it in front a spring, e², turned up at the end, in which the pen-tube lies.

F is an electro-magnet, charged by any suitable battery and key, worked by the operator; and F', the armature, secured to the side of the pen-holder e, F² being a retractile spring holding the pen-holder and pen when not acted upon by the electro-magnet, and F³ F³ stops between which the pen and holder play.

By the arrangement above described the pen, continuously fed from the fountain, is kept in constant contact with the surface of the cylinder A, and describes, in insulating-ink, a line which can be used either as the positive or negative of a message, such line being, by the combined and compound movement of the cylinder rotating and pen traveling across its surface, a spiral, but a spiral interrupted and broken by the action of the electro-magnet, although the continuity of the line is preserved by the oblique connections, all as shown at G G', Fig. 5. When the line is used negatively, the metal of the cylinder constitutes the positive of the message, and conversely.

By the construction and arrangement just described the wear and tear of the pen arising from intermittent contact with the cylinder 70 when an up and down motion is adopted are materially lessened, and there is no chance of the pen-point clogging with ink.

Any kind of message may be marked on the cylinder; but I prefer to use the code for which 75 I am applying for a patent by petition of even date herewith.

On the end of the screw-shaft B is a gear-wheel, b, a similar wheel, a, being mounted on the end of the cylinder-shaft A'. Between 8c these and intermeshing with both, so as to communicate the motion of A' to B, is an idle-wheel, a'. By this means I secure the rotation at an even rate of speed of the cylinder and screw-shaft and the accuracy of the movement of the transmitting stylus over the path of the pen. The styluses H H' will be of any approved construction and provided with suitable devices for bringing them into contact with the cylinder A and detaching them therefrom, each stylus following a direct and uninterrupted spiral path composed of alternate contacts and insulations. With these two styluses I may use, as shown in Fig. 6, two batteries, K+ and K-, sending, respectively, 95 a plus and minus current to line L, these batteries being placed upon lines l l', taken from styluses H H' to main line L, and the transmitting-cylinder A being connected to earth. By this means one stylus is in contact with the 100 cylinder A, while the other rests on the insulating-ink, and as they constantly change these positions an alternating current of differing polarity is sent to line.

Fig. 9 shows the above arrangement as constructed for repeating messages at any station intermediate between the station from which the message is dispatched and that at which it is to be received.

M is a relay, either polarized or ordinary, 110 through the magnet of which the line-current passes to earth. N is a local battery put in circuit, by means of the armature of such relay-magnet, with the line O, the current of which will operate a pen mechanism similar to that 115 already described, for the purpose of transcribing on the cylinder at the intermediate station the message to be forwarded.

Some such device as the above will be found absolutely essential when messages are to be 120 retransmitted, unless very heavy battery-power be used, in which case the main line L may be taken, as shown by the dotted lines, directly to the electro-magnet of the pen apparatus at the retransmitting station.

The method by which I propose to utilize, practically, secondary or induced currents to transmit messages in automatic telegraphy is shown in Fig. 10, in which the battery or primary circuit passes from the battery Q through 130 the transmitting-cylinder A and primary coil P back to the battery. The secondary circuit is at the transmitting-station taken at one end to earth and at the other to line passing at the

receiving - station through the recording-instrument and paper also to earth. This secondary or induced current may also be used to operate the relay just described and shown 5 in Fig. 9.

I prefer to use at the receiving-station the ordinary chemical paper properly carried over contact - plates through which the current passes to earth, the recording-instrument being 10 to any suitable point.

In Fig. 11 is shown one of the keys of my improved key-board. The front part of the key proper is formed as shown at R and of non-conducting material, the rear end of two 15 strips, R', of brass or like metal, carried by the spring S, secured to strip S', connected by line with one pole of battery Z, the other pole of which is connected with a freely-revolving metal roller, T, the length of the key-board. 20 In the strips R' are formed bearings for the metal spindle u of the disk U, in the periphery of which is set the sign V, formed of a metal segment communicating with spindle u, and having blocks of non-conducting material 25 let into it so as to give the necessary spaces in the letter. The disk U is cut away, as shown at U', and is secured to the frame by a retractile spring, W, the situation of this cut-out being fixed by the length of the sign forming 30 the letter. When the operator depresses the key, the disk U is brought into contact at an insulated point of its periphery with the roller T, which rotates it, and as each sign forming the letter comes in contact with the 35 roller T the battery - circuit is completed through the spindle u and a current sent either to the electro-magnet operating the pen mechanism or to a distant station. The dropping of the key at the cut-out U' will warn the operator of the completion of the letter, and on 40 the key being released the retractile spring W will restore the parts to their normal position. Stops arranged in the side of the disk U and in the strips R' determine the normal position 45 of the disk with relation to the continuously-revolving cylinder.

It must be understood that the improvements herein described can be used in connection with all or any of the known devices 50 for transmitting telegraphic messages automatically, and that ordinary telegraphy and telephony may be used as adjuncts thereto for the purposes of switching, signaling, and conveying messages, and that more than one instrument can be used in a station.

I am aware that the pen marking continuously upon paper wrapped upon a cylinder is not new, and that, as in the British Patent No. 2,134 of 1859, there has been shown a cylinder adapted to carry paper, and a pen carried upon a laterally-moving frame or table moving in unison with the cylinder, said pen having intermittent lateral movement caused by an electro - magnet; and I have limited my 65 claims, in view of the state of the art, accordingly.

What I claim is as follows:

1. In an automatic telegraph apparatus, the pen slitted vertically and longitudinally along the bottom, as and for the purposes described. 7c

2. In combination, a rotary transmitting-cylinder in circuit, as described, a pen mounted upon a tablet and arranged to turn laterally thereon, a transmitting - stylus, also mounted on a tablet, the tablets carrying the pen and stylus being both fitted to a screw mechanism for giving them lateral movement, an electro-magnet with its armature connected to the pen, and connections with the line-circuit for the stylus, the parts being constructed and arranged to operate substantially as described. 75 8c

3. In combination, a rotary transmitting-cylinder with telegraphic connections, as described, a pen and a transmitting - stylus adapted to bear upon the periphery of said cylinder, mechanism for giving said pen and stylus lateral motion in relation to the cylinder, and an electro-magnet for giving the pen intermittent lateral motion upon its lateral moving support, substantially as described. 85 9c

4. In combination, a rotary transmitting-cylinder with its telegraphic connections, substantially as described, a pen and stylus carried on the screw-shaft and arranged to bear on the surface of said cylinder, mechanism for holding the pen normally in line, an electro-magnet for giving it limited lateral movement on its support, and a gear connecting the screw-shaft and the shaft of said cylinder, as herein-before explained. 95 100

5. In an automatic telegraphic system, a rotary transmitting-cylinder and styluses arranged to bear thereon, line-batteries of different polarity located between the respective styluses and the line, and rotary cylinders located at an intermediate station, provided with a pen and ink-supply apparatus, said pen being arranged to bear on the periphery of the said cylinder and provided with a yielding mechanism for holding it normally in line, in combination with an electro-magnet and its armature attached to the pen on the cylinder located at said intermediate station, said electro-magnet being located in the main or local battery circuit, substantially as described. 105 110 115

6. A transmitting-cylinder in circuit, as described, a slide carried by a screw connected to the transmitting-cylinder and driven therewith, a pen carried with its fountain on a suitable tablet and adapted to turn laterally thereon, an electro-magnet, also carried on said tablet, for moving the pen laterally, a stylus with its electrical connections mounted on a suitable tablet, both tablets being constructed and arranged to fit the slide, whereby either 120 125 may be used with the same transmitting-cylinder and the message traced on said cylinder and the stylus used thereon, substantially as described.

WILLIAM AUGUSTUS LEGGO.
